Atty.

UNITED STATES PATENT OFFICE.

ALBERT W. WUNDERLICH, OF ARLINGTON, MASSACHUSETTS.

LIQUID CONTAINER.

Application filed January 21, 1922. Serial No. 530,958.

To all whom it may concern:

Be it known that I, ALBERT W. WUNDERLICH, a citizen of the United States of America, and a resident of Arlington, in the 5 county of Middlesex and State of Massachusetts, have invented certain new and useful Improvements in Liquid Containers, of which the following is a specification.

This invention relates to liquid containers 10 and has for its object the production of a device especially adapted for the use of motorists, in which a given quantity of lubricating or other oil may be sealed and which combines therewith a means of pouring the 15 oil out of the container when the seals are broken.

The invention consists primarily of a can or other receptacle having an outlet hole and a vent hole in the top which are closed by 20 seals which may be readily disconnected from the container without the use of tools.

The invention further consists in providing the container adjacent to the pouring hole with a flexible member normally positioned against the exterior wall of the container and which may be bent to form a spout at any convenient angle to said container.

The invention further consists in certain 30 novel features of construction and arrangement of parts which will be understood readily by reference to the description of the drawings and to the claims to be hereinafter given.

For the purpose of illustrating the invention, one preferred form thereof is shown in the drawings, this form having been found to give satisfactory and reliable results, although it is to be understood that the 40 various instrumentalities of which the invention consists can be variously arranged and organized, and that the invention is not limited to the precise arrangement and organization of the instrumentalities as herein shown and described, except as required by the scope of the appended claims.

Of the drawings:

Figure 1 represents a plan of an improved liquid container embodying the principles 50 of the present invention.

Figure 2 represents a plan of same with the flexible spout member bent outwardly.

Figure 3 represents a plan of same with the flexible spout member bent outwardly 55 and the seals removed.

Figure 4 represents a section on line 4, 4 on Figure 2.

Figure 5 represents an elevation of the upper end of the container showing the spout bent outwardly in position for pouring the liquid from the container, and 60

Figure 6 represents an elevation of the upper end of the container with the seals unbroken and the spout member separated from the wall thereof and showing the folds 65 therein adjacent its secured end.

Similar characters indicate like parts in the several figures of the drawing.

In the drawings 10 is the upper end of a can or container having a top plate 11 which 70 may be secured thereto in any well-known manner. This top plate 11 has an outlet hole 12 formed therein preferably near one edge, and a vent hole 13 formed therein near the opposite edge. 75

The vent hole 13 is hermetically sealed by means of the member 14 soldered thereto in any well known manner, and having projecting therefrom the tab 15 which is disconnected from the top plate 11 but normally 80 lies flat against the same. In a similar manner the outlet hole 12 is hermetically sealed by means of the member 16 soldered thereto in any well-known manner, and having a projecting tab 17 which lies flat upon 85 the top plate 11, and overlaps the end of the tab 15 as plainly shown in Fig. 2 of the drawings. These sealing members 14 and 16 are of thin flexible material and when it is desired to secure access to the oil or other 90 liquid in the container, the tab 17 is seized and the member 16 is disengaged from the top plate 11, leaving the outlet hole 12 uncovered as indicated in Fig. 3. In a similar manner the tab 15 is seized and the member 14 is disengaged from the top plate 11 leaving the vent hole 13 uncovered as indicated 95 in Fig. 3.

Adjacent to and opposite the pouring hole 12, the top plate 11 has secured thereto the flexible member 18 which in normal position has folds 19 formed therein on opposite sides of the pouring hole 12, so that said flexible member 18 may lie flat upon the top plate 11 and cover the member 16 and a portion 100 of the member 14. This positioning of the flexible member 18 on top of the free ends of the tabs 15 and 17 effectually prevents these tabs from being caught and accidentally disengaged from the top plate 11. 105 110

When it is desired to use the oil within the container 10, the outer end of the flexible member 18 is seized and first moved to the position indicated in Fig. 6 and then this member 18 is moved further in the direction of the arrow *a* on Fig. 6 of the drawings until it reaches the position indicated in Figures 2 to 5 inclusive.

This member 18 is very thin and flexible so that its sides may be bent up, forming a concave spout wider at its secured end than at the free outer end as indicated in Figures 2 and 3. The edges of the outer end may be bent closely together so that all the oil passing down the spout will be directed into any opening regardless of the size thereof.

When the spout has been properly concaved and bent outwardly into the positions indicated in Figures 2 to 5 inclusive, or at any other desired angle to the container 10, and the seals 14 and 16 have been removed from the top plate 11, the said container 10 is in condition to be tipped in order to permit the oil to pass from the pouring hole 12 down the spout 18, the vent hole 13 being open and permitting air to enter the upper part of the container 10 and facilitate the pouring.

By means of a construction such as herein described, a predetermined amount of oil may be placed in a container hermetically sealed and carried by the motorist until such time as the oil is required to lubricate parts of the motor or the running parts of the machine.

When the use of such oil is required, it is obvious that the container may be opened readily without the use of any tools, and the spout quickly positioned and shaped so that the oil when poured may be directed to any point it is desired to lubricate.

While the device shown and described is especially adapted for lubricating and other oils, it is perfectly obvious that it may be used equally as well for other liquids; as for instance, liquids used on the table or in cooking.

It is believed that the operation and many advantages of the invention will be readily understood without further description.

Having thus described my invention, I claim:

1. A liquid container consisting of a cylindrical can provided with an outlet hole in the upper wall thereof near one edge; and a thin flexible member having at one end a wide concaved edge soldered to said wall along a line concentric to the edge thereof and between said edge and outlet hole, said member being adapted to be folded flat against said wall under normal conditions but capable of being bent outwardly and concaved to form a delivery spout.

2. A liquid container consisting of a cylindrical can provided with an outlet hole in the upper wall thereof near one edge; and a thin flexible member having at one end a wide concaved edge soldered to said wall along a line concentric to the edge thereof with the opposite ends of said soldered portion aligned with the center of said hole, said member being adapted to be folded flat against said wall under normal conditions but capable of being bent outwardly to form a concaved delivery spout.

3. A liquid container consisting of a can having an outlet hole in its upper wall near one edge and a vent hole near the opposite edge; seals for covering both holes with disengaging tabs projecting toward each other and overlapping; and a flexible member secured to the edge of the can adjacent the outlet hole capable of being bent to form a concaved spout but adapted normally to lie flat upon the upper wall of said can above both tabs.

Signed by me at 746 Old South Bldg., Boston, Mass., this 20th day of January, 1922.

ALBERT W. WUNDERLICH.
